ELECTRIC TRANSPORTING DEVICE.

1,175,435.

Specification of Letters Patent. Patented Mar. 14, 1916.

Application filed July 25, 1911. Serial No. 640,517.

To all whom it may concern:

Be it known that we, HERMANN GRADENWITZ, WILHELM VOLLBRECHT, and HANS LEVZOW, citizens of the German Empire, 5 and residents of Berlin, Germany, have invented certain new and useful Improvements in Electric Transporting Devices, of which the following is a specification.

Our invention relates to improvements in 10 electric transporting devices and is intended primarily for traveling cranes and telpherage systems. And the main object of the improvements is to provide means for controlling from a distance an electric motor 15 or a plurality of electric motors located on or suspended from a crane or from a car or trolley movable on an overhead track.

The invention is especially adapted for 20 use in telpherage systems wherein a car provided with means for hoisting material such as coal or sand or ore from the ground or from the bottom of a ship transfers the material from one point to the other in order to discharge it and be returned to the 25 starting point or move on to some other point of the track. The invention, however, is applicable to the trolleys of cranes as well as to any other hoisting device.

The invention comprises the means for 30 controlling from a distance the electric motors operating said grab or grab bucket.

The invention may advantageously be used in connection with the system for controlling from a distance the electric motors 35 of a car or trolley on an overhead track as described in our Patent No. 1,039,272, of September 24th, 1912.

In the drawings, forming part of this specification we have shown two examples 40 embodying our invention as applied to a telpherage system controlled from a distance as described in our patent cited above.

Figure 1 shows in a diagrammatical way 45 the connections for controlling and operating a grab suspended from a trolley by means of a single motor. In Fig. 2 we have shown in a diagrammatical way the connections for controlling and operating a grab by means of two separate motors. In Fig. 3 50 we have shown a detail illustration of the worm shaft in Fig. 1 and the manner of controlling the electric circuit thereby.

Referring to the example illustrated in Fig. 1 of the drawings, 1 is the overhead

track, 2 the line wire, 3 the trolley, 4 the driving motor, 5 the hoisting motor, B a winch driven by said motor. At those points where it is desired to control the motors, a dead section 2' is insulated from the line wire and an auxiliary circuit 7 is branched off from the live and the dead section of the line wire, this branch leading to a starting switch 8, more fully described in the aforesaid patent. Between the trolley 3 and the motors 4 and 5 a switch drum 65 consisting of two sections 11, 12 and a solenoid 13 are located on the car. The core 14 of the solenoid is normally under the action of a spring 14^a and its lower end is connected to the part 11 of the switch drum by means 70 of a connecting rod 15 in such a manner that the core in rising against the force of the spring 14^a imparts to the part 11 a short angular movement and upon returning to its initial or normal position turns the part 75 11 back again.

The member 11 of the switch drum carries a contact plate 11^a for controlling the solenoid 13; the part 12 carries the contacts for controlling the motors. The two members 11 and 12 of the switch drum are pressed against each other by a spring 16 and are connected by means of a claw coupling 17 in such a manner, that member 11, as the core of the solenoid rises, will engage member 12 and turn it in the same direction, whereas upon its return movement member 11 will slide past member 12. The claw coupling has as many steps as there are groups of contacts on drum 12, corresponding to as many controlling positions of the switch drum. All these features are more fully described in our above patent, so that their description may safely be omitted here without impairing the clearness of the description of the apparatus.

In the examples shown in the drawings six steps are provided, corresponding to two controlling positions for the driving motor (forward and backward) and four controlling positions for the hoisting motor or motors (lowering the charged grab, discharging and lifting it, lowering the empty grab, recharging and lifting it).

The mode of controlling the motors from 105 a distance by means of the system described above has been fully pointed out in our prior patent.

According to our invention an automatic grab or grab bucket 21 is suspended from the winch B by means of a rope a cable or chain 23, and I shall use in the annexed 5 claims the term "cable" as broadly comprising either of the three. Close to and slightly below said winch another winch A is located on the car, said winch carrying another cable 22; to the free end of said cable 10 two short cables 22^a and 22^b are attached with their ends fastened to the lateral edges of the grab. The cable 23 being fastened to the pivot of the grab, on being drawn upward tends to close and lift the grab, 15 while cable 22 tends to spread the jaws of the grab apart. The winches A and B are operated from a single electromotor, *i.e.* the hoisting motor 5, by means of two separate worm gears 24 and 33, worm 24 gearing with 20 winch drum A and worm 33 gearing with winch drum B. The worms 24 are 33 are loose on the motor shaft 25, and they can be coupled with said shaft by means of friction clutches 26 and 27 respectively. The 25 clutches 26 and 27 are operatively connected with the cores of two solenoids 28 and 29. Worm 33 is provided with an externally screw-threaded cylinder 34 carrying a nut 35 shown in detail in Fig. 3; to the worm 24 30 a pin 36 is secured which extends along the cylinder 34 and through a perforation in said nut. A circumferential groove 37 is formed on nut 35. Opposite said nut the lever 38 of a switch 39 is arranged, the 35 free end of said switch lever engaging in the groove 37 of nut 35.

The way of operating and controlling the grab from a distance is as follows: If it be supposed that the grab is in its uppermost 40 position and is charged with material, in order to lower it and to discharge the material, part 12 of the switch drum is first rotated by means of the starting switch 8, the solenoid 13 and part 11 of the switch drum 45 into the position shown in Fig. 1 of the drawings. Thereby the following circuit is made: from brush 45 to contact 46, brush 47, motor 5, brush 48, contacts 49, 50, brush 51 and wire 52. At 53 the circuit is divided 50 in two branches, one branch 54 leading to the solenoid 28; after passing the solenoid the circuit is again divided in two branches at 55, one branch leading through wire 56 to brush 57, contacts 58, 59, brush 60 and to the track rail or to the ground; the other branch leading from point 55 through wire 61 to contact 62, the lever 38 and contact rail 39 to the track rail or to the ground. Therefore solenoid 28 attracts its core and 55 the clutch 26 is thereby operated to couple the worm 24 to the motor shaft 25. At the same time the current has been flowing from branch point 53, through wire 63, to solenoid 29, and after passing the solenoid winding 60 it flows through wire 64, contact 65, wire

66, brush 67, contacts 68 and 59 and brush 60 to the track rail or to the ground. The solenoid 29 is therefore excited simultaneously with solenoid 28, its core operating clutch 27 to couple the worm 33 to the motor shaft. The motor is now started by turning the handle of switch 8, and both winches are uniformly driven in the same direction, thereby allowing the hoisting rope 23 and the discharging rope 22 to unwind and grab 70 to be lowered. By switching the handle off again the grab is stopped in the desired position above the place of discharge. In order to cause the scoops of the grab to spread apart and to discharge the material, part 12 75 of the switch drum is rotated one step farther by means of starting switch 8. The circuit is now as follows: from brush 45, to contact 69, and through brush 48 and motor 5 to brush 47, through contacts 70 and 80 71 to brush 51, through wire 52 to point 53, through wire 63, solenoid 29, wire 64, contact 65, wire 66 onto brush 67. The circuit being broken at 74 and 67, the solenoid 29 is not excited. On the other hand the current 85 flows from point 53 through wire 54, solenoid 28, and to point 55, from which it passes on the one hand through wire 61, switch 62, switch lever 38, and contact rail 39 to the track rail or to the ground, and 90 on the other hand from point 55, through wire 56, brush 57, contacts 72, 73 and brush 60 to the ground.

On starting the motor, the winch A will be caused to rotate and to wind up the discharge rope 22. The scoops of the grab are spread (as shown in dotted lines) and the material is allowed to fall to the ground. While the worm 24 of the discharging winch is thus rotating, the worm 33 not being coupled to the motor shaft is at rest. The pin 36 extending from the worm 24 and through a perforation of nut 35 now causes the nut to turn on the threaded cylinder 34 fastened to worm 33, the nut being thereby displaced 105 longitudinally of shaft 25 and at the same time turning the switch lever 38 from its initial position onto contact 74 (as shown in dotted lines). The circuit is now closed from point 65, over contact 74, lever 38, and 110 contact rail 39 to ground, and the solenoid 29 being now excited attracts its core, thereby coupling worm 33 to the motor shaft and causing the hoisting winch B to wind up the hoisting rope 23, both ropes being now 115 wound up at the same speed. The grab is lifted with its jaws spread apart; by turning the handle of switch 8, the switch drum 12 may first be rotated one step into the 120 position indicated "traveling backward" 125 and the traveling motor may then be started.

After arriving at the place where the grab is to be charged, the switch drum 12 is rotated one step, in order to lower the grab with its jaws spread apart onto the material. 130

In this position of the drum the circuit is as follows: from brush 45 through contact 75, brush 47, motor 5, brush 48, contacts 76, 77, brush 51, wire 52, and to point 53. From 5 this point the current flows through wire 54, solenoid 28, point 55, wire 61, onto contact 62, and on the other hand through wire 56, brush 57, contacts 78, 79 and brush 60 onto the track rail or to the ground. The current 10 further flows from 53 through wire 63, solenoid 29, wire 64, point 65 and contact 74, and switch lever 38 (said lever still occupying the position shown in dotted lines) to the ground. At the same time the circuit 15 runs from point 65, through wire 66, to brush 67, the circuit being broken at this point. Both solenoids being thus excited, the hoisting winch as well as the discharge winch will unwind their ropes at the same 20 speed.

As soon as the open grab has come to rest upon the material to be transported, the motor is switched off and the drum 12 is rotated one step farther. In this position of 25 the drum the circuit is as follows: from brush 45, over contact 80, brush 48, motor 5, brush 47, contacts 81, 82, brush 51, wire 52, to point 53; from here through wire 54, solenoid 28, point 55, wire 61, to contact 62; 30 on the other hand from point 55, through wire 56, to brush 57, where the circuit is broken. From point 53 the current further flows through wire 63, solenoid 28, wire 64, contacts 65, 74, switch lever 38 (still in 35 dotted position), and to the ground. At the same time the current flows from point 65, through wire 66, brush 67, contacts 83, 84, and brush 60, to the track rail or to the ground. On starting the motor the hoisting 40 winch B will alone be rotated, the circuit of solenoid 28 being broken and the worm 24 not being coupled with the motor shaft. By winding up the hoisting rope 23 the grab is slowly closed, whereby it scoops up 45 material. After a certain number of turns of winch B the grab is completely closed and it is now lifted. In order to prevent the discharge rope from getting slack, the winch A should now be rotated in the same 50 direction. This is effected automatically by means of the nut 35, which has in the meantime been shifted from the position shown in dotted lines into its initial position, so that the switch lever 38 is likewise in its initial 55 position. The return movement of the nut is caused by the pin 36, which is at rest, while the threaded cylinder 34 is rotating together with the worm 33. In this position of lever 38 the solenoid 28 is again connected to the ground and the clutch 26 is therefore moved into coupling position. Both 60 winches are again rotating together and the ropes are wound up at the same speed. The drum may now be switched on to the position indicated "traveling forward" and the

driving motor be started in order to transport the material to any desired place.

In Fig. 2 of the drawings the invention is illustrated as applied to a hoisting winch and a discharge winch driven by separate 70 motors. The solenoids (154, 164) only serve to operate the motor brakes. The worm gears are fast upon the motor shafts and an electromagnetic clutch is inserted between them in order to couple both shafts whenever the winches are to operate together and at even speed. The threaded shaft and nut as well as the shaft carrying the pin for shifting the nut on its shaft are placed alongside of the motor shafts and are driven 80 by them through toothed gear wheels. With this modification of the invention the grab is operated as follows: If it be supposed that the grab is charged with material and hangs in its uppermost position close to the 85 car, and it is desired to lower it, both ropes must be unwound and lowered and the winches must be rotated in unison. This is effected by causing the switch drum 12' to assume the position shown in the drawing. 90 The circuit is now as follows: The current flows from the starting switch 8' through the solenoid 14', brush 106, ring contact 150 and contact 151 of the switch drum, brush 152, wire 153, solenoid 154, hoisting rope 95 motor 155, wire 156, brush 157, contact 158, ring contact 159, brush 160, to the track rail or to the ground. The current further flows from brush 106, through ring contact 150, contact 161, brush 162, wire 163, solenoid 100 164, spreading rope motor 165, wire 166, brush 167, contacts 168, 169, brush 200, wire 170, contact e, switch lever 171, wire 172, winding 173 of the electromagnetic clutch A, wire 174, brush 175, contacts 176, 159, brush 160, to the rail or to the ground. As soon as the current has been switched on, both motors will be started and will unwind the hoisting rope 23' as well as the spreading 110 rope 22'. The electromagnetic clutch A connected to shaft h of worm 24' being excited will attract its core B, which is loose on shaft e of worm 33', against the force of a spring f. The core B being secured against rotation on shaft e by a key g, both shafts 115 are coupled with each other and the winches I' and II' will rotate at equal speed, the ropes being unwound at the same rate. The charged grab descends and may be stopped at the desired distance above ground by 120 cutting off the current.

In order now to discharge the grab and to lift it again, the switch drum is rotated one step into the next following position ("discharging and lifting"). In this position of the drum the current flows from finger 106 through ring contact 150, contact 177, brush 167, wire 166, motor 165, solenoid 164, wire 163, brush 162, contacts 178, 159, brush 160, to the track rail or to the ground. 130

Motor 165 alone being started in inverse direction, winch I' will wind up the spreading rope 22' and the jaws of the grab will be spread apart, letting the charge fall to the ground.

In order, now, to provide for an automatic starting of the hoisting rope motor, a toothed wheel *i* on shaft *h* of winch I' meshes with a toothed wheel *k* on a threaded shaft 34' mounted in bearings *o*. A nut 35' located on said shaft 34' is prevented from rotating with said shaft by a pin 36' which is fastened to a shaft 37' running in bearings *p*, said pin protruding into a perforation formed in said nut. The rotation of motor 165 and shaft *h* is transmitted to the threaded shaft 34'; the nut being prevented from participating in this rotation is shifted in a direction parallel to the axis of shaft 34' and in being so shifted turns the switch lever 171 from its original position (shown in full lines) into the position shown in dotted lines. Thereby a second circuit is made, which passes 20 from brush 106, to contact 150, 179, brush 175, wire 174, winding 173 of electromagnetic clutch A, B, wire 172, switch lever 171, contact *d*, wire 180, brush 181, contacts 182, 183, brush 157, wire 156, motor 155 of the 25 hoisting winch, solenoid 154, wire 153, brush 152, contacts 184, 159, brush 160, and to the track rail or to the ground. The motor 155 of the hoisting winch is started in the inverse direction at that moment, 30 when the switch lever 171 has been turned on contact *d* by means of nut 35'. The hoisting rope winch II' is now likewise rotated, so as to wind up the hoisting rope. The movement of the nut 35' on its screw 35 threaded shaft 34' is finished when the shaft 37', which is coupled to the worm 33' of the hoisting winch shaft by means of gear wheels *l* and *m* and which carries the pin 36', begins rotating; for now the pin 36' rotates around the screw threaded shaft 34', so that it does not prevent any more the rotation of nut 35'. Both winches are now driven at the same speed, because, when starting the hoisting winch motor 155, the winding 173 of the electromagnetic clutch A is energized, thereby attracting its core B and coupling both worms 24' and 33' respectively. Therefore the grab, from 40 which the material has been discharged, is lifted with its jaws spread apart. Upon its arrival in its uppermost position the switch drum is rotated one step into the position, in which it supplies current to the driving motor. The trolley returns to its starting point, where it is arrested by throwing the starting switch into inoperative position. Now the empty grab must be lowered on the material. For this purpose the switch drum is again rotated one 45 step. The connections are the same as has

been described before, except that the contacts are disposed in such a way, that the direction of the current in both motors 155 and 165 is the reverse, so that the motors are now driven in the opposite direction 70 and both ropes are unwound. The switch lever 171 is still on contact *d*, so that also in this case the electromagnetic clutch A attracts its core B and couples both worms with each other.

Now the grab is lying on the material with its jaws spread apart, and it must now grab the material, close its jaws and move upward. For this purpose the switch drum is further rotated one step. Now the current passes from brush 106 over contacts 150, 190, brush 157, wire 156, motor 155 of the hoisting rope, solenoid 154, wire 153, brush 152, contacts 191, 159, brush 160 and to the track rail or to the ground. The motor 155 is started in opposite direction, the hoisting rope is wound up and thereby closes the jaws of the grab. The gear *l*, which is mounted on the shaft *e*, drives the gear wheel *m*; the shaft 37' and its pin 36' rotate, 80 so that the latter moves the nut 35' from its position shown in dotted lines into its original position, whereby the switch lever 171 is again turned from contact *d* to contact *c*. Thereby a second circuit is made for 85 the current, which passes from brush 106 over contacts 150, 192, to brush 175, wire 174, winding 173 of the electromagnetic clutch A, wire 172, switch lever 171, contact *c*, wire 170, brush 200, contacts 193, 194, brush 167, 90 wire 166, motor 165 of the spreading rope, solenoid 164, wire 163, brush 162, contacts 195, 159, brush 160, and to the track rail or to the ground. The motor 165 of the spreading rope is now likewise started and winds 95 up the spreading rope. The electromagnetic clutch A, B couples the worm shafts *e* and *h*, so that the hoisting rope and the spreading rope are uniformly wound up. The charged grab is lifted and the switch 100 drum can be set on the position indicated "traveling forward," whereby the driving motor is started in opposite direction and the trolley travels with the charged grab 105 back to the place of discharge.

We claim:

1. An operating device for a grab, comprising a hoisting winch with a cable from which the grab is suspended, a discharging winch with a cable controlling the opening and closing of the grab scoops, operating gearing for each winch, a hoisting motor for both gearings, a coupling between each gearing and said motor, electromagnetic means for actuating each of said couplings 120 separately, a source of electric supply, said electromagnetic means and said motor being in the circuit of said source, a main switch for controlling the direction of the current in said circuit and an automatic 125

switch in the circuit, said automatic switch being actuated by said gearings in such a manner that it will be set in readiness for the next step of operation of the device.

5 2. An operating device for a grab, comprising a hoisting winch with a cable from which the grab is suspended, a discharging winch with a cable controlling the opening and closing of the grab scoops, operating 10 gearing for each winch, a hoisting motor for both gearings, a coupling between each gearing and said motor, electromagnetic means for actuating each of said couplings separately, a source of electric supply, said 15 electromagnetic means and said motor being in the circuit of said source, a main switch for controlling the direction of the current in said circuit and an automatic switch in the circuit, said automatic switch comprising-

ing a threaded revoluble member positively 20 driven by one of said gearings, a nut on said revoluble member similarly driven by the other one of said gearings and a lever having connection with said nut and provided with contact points, said lever being 25 oscillated by said nut during its axial travel, said automatic switch being actuated by said gearings in such a manner that it will be set in readiness for the next step of operation of the device. 30

In testimony whereof we affix our signatures in presence of two witnesses.
